CONVERSION OF HYDROCARBONS

Carl B. Linn and Vladimir N. Ipatieff, Riverside,
Ill., assignors to Universal Oil Products Com-
pany, Chicago, Ill., a corporation of Delaware

Application November 25, 1942, Serial No. 466,925

19 Claims. (Cl. 196—9)

This invention relates to the conversion of hydrocarbon oils and particularly of hydrocarbon fractions produced by the distillation of petroleum oils, coal, and other hydrocarbonaceous materials. In a more specific sense, the invention is concerned with a modification of hydrocarbon oil conversion processes involving the use of particular and specific types of catalysts which function to promote the formation of a relatively high yield of high quality gasoline from hydrocarbon oils such as crude oil, topped crude, gas oil, naphtha, kerosene, low antiknock gasoline, and also oils from sources other than petroleum.

The cracking of relatively heavy hydrocarbon oils to produce primarily gasoline or gas has been carried out by many methods and it is recognized that large numbers of the basic principles of hydrocarbon decomposition are known and that particular commercial processes have been developed which embody these principles. However, the application of catalysts to cracking of hydrocarbon oils is still largely empirical and it is not possible to predict just what catalysts should be employed to produce maximum yields of desired product when cracking different fractions of different petroleums or other different hydrocarbon oils. A large number of solid catalysts have been developed for catalytic cracking which comprise various raw and acid treated clays, synthetically prepared composites comprising silica and at least one member of the group consisting of alumina, magnesia, and zirconia. Other processes are known according to which a hydrocarbon oil is subjected to a cracking temperature in the presence of an alkyl halide, particularly an alkyl chloride or bromide, these halogenated paraffins being sometimes employed simultaneously with synthetically prepared or clay-type cracking catalysts.

The present invention is concerned with the cracking of hydrocarbon oils in the presence of at least one of a group of fluorine-containing compounds which are substantially gaseous at 25° C. and under a pressure of 1 atmosphere. These volatile catalysts are characterized by selectivity in accelerating gasoline-forming reactions rather than gas-forming reactions, by their property of being readily mixed with the hydrocarbons subjected to treatment, and by other factors.

One specific embodiment of the present invention relates to a process for converting hydrocarbon oils into substantial yields of gasoline which comprises heating said oil under cracking conditions in the presence of phosgene and of at least

one fluorine compound selected from the group consisting of hydrogen fluoride, boron fluoride, and carbonyl fluoride.

According to the present invention, a hydrocarbon oil or a fraction thereof is treated at a temperature of from about 300° to about 700° C. in the presence of a small amount of phosgene and of at least one compound selected from the group consisting of hydrogen fluoride, boron fluoride and carbonyl fluoride. Generally not more than about 5% by weight of any one of the above mentioned halogen compounds is commingled with the hydrocarbon oil or its vapors prior to being subjected to the heat treatment. While the process of this invention may be carried out under substantially atmospheric pressure, it is preferable to employ a superatmospheric pressure which is generally less than about 60 atmospheres in order to increase the capacity of the treating equipment to produce a good yield and high quality gasoline. Thus, a hydrocarbon oil may be treated in the presence of about 5% by weight of phosgene and about 5% of hydrogen fluoride or in the presence of about 5% by weight each of phosgene, hydrogen fluoride, boron fluoride and carbonyl fluoride to produce a substantial yield of lower boiling hydrocarbons with high antiknock value suitable as gasoline.

It is sometimes advantageous to mix a butane fraction, and particularly isobutane, with a naphtha or other hydrocarbon oil prior to treatment with phosgene, hydrogen fluoride, and/or boron fluoride and/or carbonyl fluoride in order to effect interaction between said butane fraction and the decomposition products of the oil.

The process may be carried out as a batch type of operation in which the oil is heated in contact with the catalyst for a time sufficient to effect substantial decomposition into relatively lower boiling products of gasoline boiling range, said products being separated by suitable fractional distillation of the reaction mixture recovered from the batch type operation.

It is preferable, however, to carry out the process in a continuous manner by simultaneously charging the hydrocarbon oil and the catalyst to a reaction zone maintained at the desired operating temperature and through which passes a mixture of hydrocarbons and catalyst. The resultant reaction mixture is then separated into hydrocarbons of gasoline, boiling range, hydrocarbons boiling higher than gasoline, and gaseous products containing fluorine compounds at least part of which may be recycled to further contact with fresh and recycled oil to assist in

its conversion. The recovered hydrocarbons boiling higher than gasoline are recycled to commingle with the fresh charge of hydrocarbons and catalyst which are introduced continuously to the reaction zone.

The process of the present invention is also applicable to the conversion of low antiknock value gasolines and naphtha, into gasolines of higher octane number by methods commonly referred to as reforming.

For the purpose of illustrating the present process, the accompanying drawing is given which illustrates diagrammatically one specific apparatus utilizable for producing gasoline of high antiknock value from a hydrocarbon oil in the presence of phosgene and of at least one of the fluorine compounds selected from the group consisting of hydrogen fluoride, boron fluoride, and carbonyl fluoride.

Referring to the diagrammatic drawing, fresh charging stock, preferably gas oil, naphtha or kerosene, is directed through line 1 and valve 2 to pump 3 which discharges through line 4 and valve 5 into coil 6 which receives heat from heater 7 to increase the temperature of said oil to the desired reaction temperature. From coil 6, the heated oil passes through line 8, valve 9, and line 10 to the top of reactor 11. If the charging stock should not be substantially completely vaporized under the chosen reaction conditions, valve 9 is closed and the heated oil is passed from line 8 through line 12 containing valve 13 to flash chamber 14 in which the vapors are separated from higher boiling residual material, the latter being withdrawn from the system through line 15 and valve 16 to storage or other use not illustrated in the drawing. From flash chamber 14 the vapors are directed through line 17, valve 18, and lines 8 and 10 to reactor 11 already mentioned.

The mixture of phosgene and at least one of the fluorine-containing compounds mentioned above, which mixture is preferably dissolved in oil or commingled with oil, is simultaneously directed through line 19 and valve 20 to pump 21 which discharges through line 22 and valve 23 into line 10 already mentioned which contains valves 24 and 25 and through which the oil containing halogen compounds may be introduced in the proper proportion into either the stream of oil being treated or the stream of heated vapors of said oil. The halogen compounds may also be introduced simultaneously through both valve 24 and valve 25. Thus, with valve 25 closed, the mixture of phosgene and fluorine-containing compound or compounds may be added through line 10 and valve 24 to the stream of oil being charged through line 4 to heating coil 6, or with valve 24 closed said mixture may be passed through line 10 and valve 25 and admixed with the oil vapors just prior to introduction into reactor 11. It is preferable to use the latter method, particularly when charging heavy oil which makes it necessary to use flash chamber 14.

The vaporized mixture of hydrocarbons, phosgene, and fluorine-containing compounds is passed downwardly through reactor 11 and the components of said mixture are intimately contacted in said reactor under the operating conditions hereinabove set forth whereby the oil is cracked to produce a high yield of a gasoline fraction of high octane number. From reactor 11 the reaction products are withdrawn through line 26 and valve 27 and passed through cooler 28 and line 29 containing valve 30 into separator 31 of

suitable design for collecting heavy tarry material formed during the reaction. Said heavy tarry material is withdrawn from the bottom of separator 31 through line 32 and valve 33 while the vapors are directed through line 34 and valve 35 to fractionator 36 of adequate design suitable for separating light gases and gasoline from higher boiling hydrocarbons.

Fractionator 36 is operated so as to produce an overhead fraction containing substantially no material boiling higher than gasoline and a distillation residue consisting of hydrocarbons boiling above the gasoline range. The overhead vapors from fractionator 36 are directed through line 37 and valve 38 to condenser 39 and thence through run down line 40 and valve 41 to receiver 42 equipped with conventional gas release line 43 containing valve 44 and with liquid drawoff line 45 containing valve 46. Uncondensed gases which are released through line 43 and valve 44 contain not only hydrogen and light hydrocarbons but also hydrogen fluoride and other fluorine-containing compounds, some of which are suitable for recycling to the heating coil or reactor by means not illustrated in the drawing.

The gasoline fraction is directed from receiver 42 through liquid drawoff line 45 and valve 46 to pump 47 which discharges through line 48 and valve 49 into line 50 containing valves 51 and 52.

A major proportion of said gasoline is withdrawn from line 50 through valve 51 to storage or other use while a portion of the gasoline is directed from line 50 through valve 52 to the top of fractionator 36 to serve as reflux liquid and thus assist in controlling the temperatures with fractionator 36.

From the bottom of fractionator 36, the hydrocarbon material boiling higher than gasoline is withdrawn through line 53 and valve 54 by pump 55 which discharges through line 56 and valve 57 into line 4 in which it is mixed with fresh charging stock and is thence directed to heating coil 6. A portion of the oil being recycled through line 56 may be withdrawn therefrom through line 58 and valve 59 to storage or other use not illustrated in the diagrammatic drawing.

Because the heavy oil which is recycled through line 56 has been subjected to the cracking treatment, it contains a greater proportion of more refractory hydrocarbons than does the original oil and consequently it gives lower yields of gasoline than does the fresh charging stock. Accordingly, in order to substantially avoid fluctuations in the operation of the process of this invention, we prefer to vary the amount of phosgene and fluorine-containing compound introduced to the reaction zone to compensate for variations in the amount and refractoriness of the recycle stock, more of the halogen-containing compounds being introduced as the amount of recycle stock and its refractoriness increase.

It will be apparent to one skilled in the art that other types of apparatus may be used for carrying out the process of this invention, and that many features not shown or described herein would normally be included in hydrocarbon cracking equipment, such as heat exchangers, controls, etc. Also a plurality of reactors could be provided and arranged for either series or parallel operation.

The following examples are given to indicate results expected in the operation of the process, although the examples should not be misconstrued to limit the broad scope of the invention.

Example I

A gas oil fraction and 5% each of phosgene and hydrogen fluoride based upon the weight of said oil are charged through a heating coil to a reactor maintained at a temperature of about 500° C. and under a pressure of 10 atmospheres and the reaction mixture is passed thence to a suitable fractionating system from which gasoline line is recovered while a substantial proportion of the higher boiling liquid products and gaseous products are recycled to the heating coil. Under the mentioned operating conditions, about 80% by volume of gasoline of 75 octane number is formed.

Example II

A naphtha boiling between 150° and 250° C. is mixed with about an equal molecular proportion of a butane fraction consisting largely of isobutane. The resultant hydrocarbon mixture is then heated to a temperature of 500° C. under a pressure of about 2 atmospheres and commingled with 5% by weight of phosgene, 5% of hydrogen fluoride, and 1% of boron fluoride. The whole reaction mixture is then maintained at 500° C. for a time sufficient to effect reaction of said isobutane and naphtha to give an 80% yield of a product boiling mainly in the gasoline range and having an octane number of 77.

The character of the present invention is evident from the preceding specification and examples, although neither section is intended to limit unduly its generally broad scope.

We claim as our invention:

1. A process for converting a hydrocarbon oil which comprises heating said oil in the presence of both phosgene and at least one of the normally gaseous compounds of fluorine selected from the group consisting of hydrogen fluoride, boron fluoride, and carbonyl fluoride.

2. A process for converting a hydrocarbon oil into a substantial yield of gasoline which comprises heating said oil under cracking conditions in the presence of both phosgene and at least one of the normally gaseous compounds of fluorine selected from the group consisting of hydrogen fluoride, boron fluoride, and carbonyl fluoride.

3. A process for converting a hydrocarbon oil into a substantial yield of gasoline which comprises heating said oil to a temperature of from about 300° to about 700° C. in the presence of both phosgene and at least one of the normally gaseous compounds of fluorine selected from the group consisting of hydrogen fluoride, boron fluoride, and carbonyl fluoride.

4. A process for converting a hydrocarbon oil into a substantial yield of gasoline which comprises heating said oil to a temperature of from about 300° to about 700° C. under a pressure of from about 1 to about 60 atmospheres in the presence of both phosgene and at least one of the normally gaseous compounds of fluorine selected from the group consisting of hydrogen fluoride, boron fluoride, and carbonyl fluoride.

5. A process for converting a hydrocarbon oil into a substantial yield of gasoline which comprises heating said oil to a temperature of from about 300° to about 700° C. in the presence of both phosgene and at least one of the normally gaseous compounds of fluorine selected from the group consisting of hydrogen fluoride, boron fluoride, and carbonyl fluoride, each of the halogen compounds so employed being present in an amount not more than about 5% by weight of said hydrocarbon oil.

an amount not more than about 5% by weight of said hydrocarbon oil.

6. A process for converting a hydrocarbon oil into a substantial yield of gasoline which comprises heating said oil and a butane fraction under cracking conditions in the presence of both phosgene and at least one of the normally gaseous compounds of fluorine selected from the group consisting of hydrogen fluoride, boron fluoride, and carbonyl fluoride.

7. A process for converting a hydrocarbon oil into a substantial yield of gasoline which comprises heating said oil and a butane fraction to a temperature of from about 300° to about 700° C. in the presence of both phosgene and at least one of the normally gaseous compounds of fluorine selected from the group consisting of hydrogen fluoride, boron fluoride, and carbonyl fluoride.

8. A process for converting a hydrocarbon oil into a substantial yield of gasoline which comprises heating said oil and a butane fraction to a temperature of from about 300° to about 700° C. under a pressure of from about 1 to about 60 atmospheres in the presence of both phosgene and at least one of the normally gaseous compounds of fluorine selected from the group consisting of hydrogen fluoride, boron fluoride, and carbonyl fluoride.

9. A process for converting a hydrocarbon oil into a substantial yield of gasoline which comprises heating said oil and a butane fraction to a temperature of from about 300° to about 700° C. in the presence of both phosgene and at least one of the normally gaseous compounds of fluorine selected from the group consisting of hydrogen fluoride, boron fluoride, and carbonyl fluoride, each of the halogen compounds so employed being present in an amount not more than about 5% by weight of said hydrocarbon oil.

10. A process for converting a hydrocarbon oil into a substantial yield of gasoline which comprises heating said oil and a butane fraction to a temperature of from about 300° to about 700° C. under a pressure of from about 1 to about 60 atmospheres in the presence of both phosgene and at least one of the normally gaseous compounds of fluorine selected from the group consisting of hydrogen fluoride, boron fluoride, and carbonyl fluoride, each of the halogen compounds so employed being present in an amount not more than about 5% by weight of said hydrocarbon oil.

11. A process for converting a hydrocarbon oil into a substantial yield of gasoline of high antiknock value which comprises heating said oil to a temperature of from about 300° to about 700° C. under a pressure of from about 1 to about 60 atmospheres in the presence of phosgene, hydrogen fluoride, and boron fluoride.

12. A process for converting a hydrocarbon oil into a substantial yield of gasoline of high antiknock value which comprises heating said oil to a temperature of from about 300° to about 700° C. under a pressure of from about 1 to about 60 atmospheres in the presence of phosgene and hydrogen fluoride.

13. A process for converting a hydrocarbon oil into a substantial yield of gasoline of high antiknock value which comprises heating said oil to a temperature of from about 300° to about 700° C. under a pressure of from about 1 to about 60 atmospheres in the presence of phosgene and hydrogen fluoride.

60 atmospheres in the presence of phosgene and boron fluoride.

14. A process for converting a hydrocarbon oil into a substantial yield of gasoline which comprises heating said oil and a butane fraction to a temperature of from about 300° to about 700° C. in the presence of phosgene, hydrogen fluoride, and boron fluoride.

15. A process for converting a hydrocarbon oil into a substantial yield of gasoline which comprises heating said oil and a butane fraction to a temperature of from about 300° to about 700° C. in the presence of phosgene and hydrogen fluoride.

16. A process for converting a hydrocarbon oil into a substantial yield of gasoline which comprises heating said oil and a butane fraction to a temperature of from about 300° to about 700° C. in the presence of phosgene and boron fluoride.

17. A process for converting a hydrocarbon oil into a substantial yield of gasoline which com- 20

prises heating said oil and a butane fraction to a temperature of from about 300° to about 700° C. under a pressure of from about 1 to about 60 atmospheres in the presence of phosgene and carbonyl fluoride.

18. A process for converting a hydrocarbon oil into a substantial yield of gasoline which comprises heating said oil and a butane fraction to a temperature of from about 300° to about 700° C. under a pressure of from about 1 to about 60 atmospheres in the presence of phosgene and hydrogen fluoride.

19. A process for converting a hydrocarbon oil into a substantial yield of gasoline which comprises heating said oil and a butane fraction to a temperature of from about 300° to about 700° C. under a pressure of from about 1 to about 60 atmospheres in the presence of phosgene and boron fluoride.
